Application November 10, 1937, Serial No. 173,850

15 Claims.

(Cl. 184—6)

The present invention relates to improvements in lubricating devices for machine tools, and more particularly to means well adapted for lubricating certain moving parts of a milling machine of the general type having a longitudinally reciprocable work table, a transversely movable saddle support, and a vertically adjustable knee support.

It is an object of the present invention to provide a novel lubrication system of the non-return type which is well adapted for supplying lubricant economically and efficiently to the various moving parts mounted in the vertically adjustable knee of a milling machine.

More specifically, it is an object of the invention to provide a lubricating system of this general description which is well adapted to provide intermittent lubrication under pressure to the various moving parts at intervals which will bear a definite relation to the extent and character of the machine operation to insure an adequate but not excessive supply of lubricant to the moving parts, and in which the amount supplied will be substantially equal to the amount of oil consumed or lost incidental to the use of the machine.

It is another object of the invention to provide a device for controlling the operation of a machine tool pressure lubricating system which is well adapted for automatic operation to supply a limited amount of lubricant to the operating parts only when the machine is returned to active operation after a substantial period of rest.

While the several features of applicants' invention are hereinafter disclosed, and are of particular value as applied to the lubrication of the moving parts in the knee of a milling machine, it will be understood that the invention in its broader aspects is not limited in its application to the specific machine or parts thereof herein disclosed, and that the lubricating system herein-after described, may be equally well applied to provide automatic lubrication for other moving parts and for other types of machine tool.

With the above noted and other objects in view, as may hereinafter appear, the several features of the invention consists in the devices, combinations and arrangement of parts hereinafter described and claimed, which together with the advantages to be obtained thereby, will be readily understood by one skilled in the art from the following description taken in connection with the accompanying drawings, in which Fig. 1 is a view in left side elevation illustrating particularly the vertically adjustable knee of a milling

machine, a portion of the knee casing having been broken away, and certain of the underlying parts being shown in section to illustrate the embodiment of applicants' lubricating devices in the machine; Fig. 2 is an enlarged detail sectional view of the oil pump and connections therefrom shown in Fig. 1; Fig. 3 is an enlarged detail sectional view of the automatic oil feed control valve shown in Fig. 1; Fig. 4 is an enlarged view in front elevation of substantially the parts shown in Fig. 1, to illustrate particularly the application of applicants' lubricating system to the moving parts in the knee and feed box of the machine; Fig. 5 is a sectional view taken on the line 5—5 of Fig. 4, to illustrate certain of the driving connections mounted in the knee; Fig. 6 is a detail view, partly in section, taken on the line 6—6 of Fig. 4, to illustrate particularly the pipe connections for lubricating the cross feed screw clutch and bearing surfaces associated therewith; Fig. 7 is a detail plan view partly in section, taken on the line 7—7 of Fig. 4, illustrating the knee elevating shaft and the conduits through which lubricant is supplied thereto; Fig. 8 is a sectional view in left side elevation taken on the line 8—8 of Fig. 4, and illustrating particularly the connections for lubricating the bearings and other moving parts in the feed box; and Fig. 9 is a plan view of substantially the parts shown in Fig. 8.

The invention is disclosed in the drawings in a preferred form, as embodied in a milling machine of the general type having a vertically extending column supporting a milling cutter spindle, and a work supporting assembly including a longitudinally movable table, a transversely movable saddle support, and a vertically adjustable knee. Only so much of the machine is illustrated as is believed necessary to illustrate the application of applicants' improved lubricating system to the moving parts mounted in the knee support and in the feed box, which is mounted to form an integral unit therewith.

The drawings disclose a vertically adjustable knee support 20 which is supported for vertical movement with relation to a machine column 22 generally indicated in Fig. 1, on ways 24, and a transversely movable saddle support 26 carried on ways 27 formed on the upper side of the knee. For a more complete illustration of the saddle support 26 and work supporting table, not here shown, together with portions of the driving transmission for operating the table, reference may be had to the copending application of the present applicant Bennett, Serial No. 173,

851, filed November 10, 1937, of even date here-with upon which has issued Patent No. 2,190,858, dated February 20, 1940. The power drive for the table, saddle and knee transmissions, is taken from a vertically extending drive shaft 28 (see Fig. 8) which may be regarded as the prime mover and is mounted in the machine column 22. From the drive shaft 28, the drive is taken through a bevel gear 30 splined thereto, and connected through a bevel gear 32 to a gear 34 secured to a drive shaft 36 in a feed box 38 which is formed integrally with the knee support 20. A second gear 40 on the shaft 38, meshes with a gear 42 forming part of an overrunning device through which is driven a shaft 44 and gear 46. The gear 46 meshes with an idler gear 47 carried on a stub shaft 48, and through this gear drives a cam driving gear 49 and a forwardly extending drive shaft 50 secured thereto, mounted in the knee support 20. The branch transmissions utilized for power operation of the individual knee, saddle and table supports, and for power operation of the lubrication devices herein described, are taken directly from the gear 49 and shaft 50 which, therefore, form the main stem of the driving transmissions for these parts.

Referring particularly to Fig. 8, it will be seen that the spline gear 30 is externally supported in a bearing 52 formed in an extension 54 of the feed box casing 38 which also provides a pivotal bearing support 56 for the intervening bevel gear 32. Bearing supports 58 and 60 are provided for the intermediate drive shaft 36, bearings 62 and 64 are provided for the overrunning clutch shaft 44 and bearings 66 and 68 for the idler gear shaft 48.

The table support (not shown) is driven from the shaft 50 through a branch transmission which comprises a bevel gear 70 splined to the shaft 50, and arranged to mesh with a gear 72 at the lower end of an upwardly extending drive shaft 74. The bevel gear 70 is externally supported in a downward extension of a housing 76 for the shaft 74 which is secured to the under side of the saddle support 26, so that these parts are movable as a unit with the saddle axially of the shaft 50.

The saddle support 26 is power operated from the shaft 50 through a branch transmission comprising a screw shaft 78 which is screw-threaded into a nut 80 formed in the housing 76, and is supported at its forward end in a bearing 82 (see Fig. 6) in the knee support 20. The screw shaft 78 may be driven from the shaft 50 through connections which include a gear 84 sleeved on the shaft 78, and a driving gear 86 supported co-axially with the shaft 50, and arranged to be driven therfrom through reversing and clutching devices hereinafter more fully set forth. As best shown in Fig. 6, the gear 84 is carried on a clutch sleeve 88 loosely supported on the shaft 78, and is connectible to drive the shaft 78 through the engagement of clutch surfaces 90 formed on adjoining portions of the clutch sleeve 88 and a collar 92 secured to the shaft 78.

For effecting a power adjustment of the vertical position of the knee support 20, an additional branch transmission is provided which may be driven from the shaft 50, and comprises a drive shaft 94 which is located parallel to and beneath the shaft 50, and at its rear end carries a bevel gear 96 which meshes with a gear 98 rigidly secured to the upper end of the usual knee adjusting screw 100. The shaft 94 is driven from

the shaft 50 through driving and reversing connections which include a reversing sleeve gear 102 which is splined to the shaft 50, and is axially movable thereon between the position shown in Fig. 5, in which it is operatively connected to drive the gear 86 sleeved thereon through the engagement of the face clutch surfaces 104, as shown in Fig. 5, and an alternative position in which it is moved to the left, causing the clutch 104 to be disengaged, in which the gear 102 meshes with an idler reversing gear 106 (see Fig. 1) carried on a stub shaft 108. A shifting yoke generally indicated at 109 in Fig. 1, provides a convenient means for controlling the position of the reversing gear 102. The gear 106 meshes with a gear 110 supported on a sleeve member 112 splined to and axially shiftable on the shaft 94. The sleeve 112 also carries a gear 114 which meshes with the drive gear 86, and is arranged through the engagement of clutch surfaces 116 formed respectively on the sleeve 112 and on a collar 118 on the shaft 94 to be operatively connected to drive the shaft 94. A shifting yoke generally indicated at 120 in Fig. 5, is provided for shifting the sleeve member 112 axially to engage or disengage the clutch 116.

Manual operation of the driving screw 78 to effect adjustment in the position of the saddle support 26, is effected by means of a hand wheel 124 (Fig. 6) which is operatively connected to the forward end of the screw shaft 78. Manual operation of the adjusting screw 100 for raising and lowering the knee support 20, is effected through connections which, as best shown in Figs. 1 and 7, include a hand wheel 122 operatively connected to one end of a horizontally extending shaft 123 which is supported in bearings 124 and 125 on the knee 20, and has secured to the rear end thereof a bevel gear 126 which meshes with bevel gear 98 secured to the upper end of the vertical adjusting screw 100.

With the construction and arrangement of the driving and reversing mechanism for the knee and saddle branch transmissions above set forth, it will readily be seen that the drive for power operation of these parts, is taken from the shaft 50 onto the reversing clutch gear 102, and thence through the clutch 104 and gear 86 directly to the respective shafts 78 and 94, or alternatively from the gear 102 onto the idler reversing gear 106, thence through gear 110, sleeve 112 and gear 114 which meshes with and operates to drive the gear 86 in the opposite direction. Inasmuch as the mechanism for shifting the reversing gear 102 and for operatively engaging and disengaging the clutch connections to the saddle and knee branch transmissions, form no part specifically of the present invention, no specific description or illustration thereof is considered necessary.

In carrying out the present invention, a lubrication system of the non-return type is provided for automatically maintaining an adequate lubrication of the moving parts which are mounted in the knee and adjoining feed box, and are comprised of the transmission trains for the table, saddle and knee. Applicants' lubricating system takes the form of a self-contained unit mounted in the knee, and is constructed and arranged to supply lubricant to the several moving parts mounted in the knee and feed box in relatively small amounts, and at intervals which will bear a definite relation to the extent and character of the machine operation. It has been found, particularly when the machine is allowed

to stand idle for any substantial period of time, that the lubricant adhering to the bearing surfaces, tends to drain off, and also as the machine cools, becomes more viscous, losing much of its efficiency and covering power. To insure proper lubrication of the operating parts when the machine is again started, applicants provide means operative automatically in starting the machine to supply fresh lubricant to the operating parts in quantities and at a pressure which will be adequate to insure a thorough lubrication of the parts at this time. It has been found also that a limited quantity of lubricant supplied in this manner will provide adequate lubrication of the machine parts through a considerable period of continuous or substantially continuous use of the machine.

In accordance with the ideas above expressed, applicants have provided a self-contained lubricating system mounted in the knee which includes a reservoir 130 mounted on the knee support 20, a pump generally indicated at 132 driven from an eccentric cam 134 formed integrally with the constantly driven gear 49 on the shaft 50, a system of conduits through which lubricant is distributed in proportionate amounts to the several bearings and other parts to be lubricated, together with a time delay control valve 136 which is operative to cause a limited amount of lubricant to be forced through the lubricating system in starting the machine only after a substantial period of inactivity.

Referring specifically to Figs. 1 and 2 of the drawings, the pump 132 comprises a casing supported within the reservoir 130 and having formed therein a central bore 140 adapted to receive a piston 142 forming the lower end of an actuating plunger 144 which extends upwardly through a bore 146 in the cover plate 148 of the reservoir 130, and at its upper end engages against the eccentric driving cam 134. A compression spring 150 coiled about the plunger 144 between a collar 152 and an abutting portion of the pump casing 132, maintains the piston 142 and plunger 144 in engaging contact with the cam 134. Lubricant is admitted into the pump chamber 140 through a filter 154 and a check valve 156 during the upward stroke of the piston 142, and during the return or down stroke of the piston 142, is forced out of the chamber 140 through a check valve 158 and a conduit 160 to the time delay valve 136 above referred to, and thence through the operation of the valve 136, as hereinafter more fully set forth, is either returned to the reservoir 130 through an exhaust outlet 161 and return conduit 162, or is alternatively directed through an outlet 164 and a conduit 166 to a main distributing head 168 to effect the lubrication of the several operating parts. An oil gauge 167 mounted on the side of the knee, and connected through a conduit 169 with the conduit 166 (see Fig. 1) provides a direct reading of the lubricant pressure in the distributing system hereinafter described.

The distributing system through which lubricant is directed in proportional amounts to the several moving parts located in the knee support 20 and feed box 38, may be briefly described with reference to the drawings as follows: The distributing head 168 is provided with a number of outlets, each having a drip plug and a branch conduit connected thereto, through which lubricant is directed to each of a number of lubricating stations. The several branch conduits are designated respectively at 170, 172, 174, 176, 178,

180, 182, and 184. Lubricant passes from the distributing head 168 through a drip plug 188 and conduit 170 into a centrally located bore 190 in the supporting shaft 108 for the idler reversing gear 106 (see Fig. 1), and thence through a radial outlet to the gear bearing, a second branch conduit 191 providing lubricant to the front bearing for the knee power drive shaft 94. Lubricant is directed from the distributing head 168 through 10 conduit 172 to a subsidiary distributing head 196 located in the feed box 38, being distributed thence through additional branch conduits to lubricate the several moving parts in the feed box, as hereinafter more fully set forth. Lubricant is directed through conduit 174 and a drip plug 198 connected therein (see Fig. 1) to the rear bearing 199 for the main drive shaft 50. The conduit 176 and a drip plug 200 associated therewith, are arranged to direct lubricant to the 20 bearing support for the hand elevating control shaft 123 (see Figs. 1, 4 and 7). The conduit 178 and a drip plug 202 associated therewith, are arranged to supply lubricant to the rear bearing support 203 for the power knee elevating shaft 94 (see Figs. 1, 4 and 5). The conduit 180 having a drip plug 206 associated therewith, is connected into the conduit 172 (see Fig. 4), and is arranged to direct lubricant to the front bearing support 82 for the cross feed screw shaft 78, and 30 thence through a branch conduit 208 to the clutch sleeve member 88 supported on the shaft 78 (see Fig. 6). The conduit 182 and a drip plug 210 associated therewith, serve to direct lubricant to the upper end of the elevating screw 100, and 35 thence through branch conduits to the several bearing surfaces associated with the screw shaft 100 including the threaded portion thereof. The conduit 184 and a drip plug 212 associated therewith, serve to direct lubricant to the external bearing support 213 for the assembly including 40 the sleeve gear 86, sleeve gear 102, and the front end of the drive shaft 50 (see Figs. 1 and 5). It will be understood that each of the drip plugs associated with the several conduits leading from 45 the distributing head 168, is constructed and arranged to provide a predetermined resistance to the passing of lubricant therethrough, so that lubricant will be distributed to the several operating parts in properly proportioned amounts 50 which may be readily determined in accordance with the requirements of the particular bearings or other parts to be lubricated.

In order to provide for lubrication of the several bearings in the feed box 38, lubricant supplied to the subsidiary distributing head 196 through conduit 172, is redistributed in proportional amounts through a number of branch conduits numbered respectively 220, 222, 224, 226, 228, 230, and 232, to a number of lubricating stations in the feed box. As best shown in Figs. 8 and 9 of the drawings, lubricant supplied under pressure to the subsidiary distributing head 196, is directed through the conduit 220 and an associated drip plug 234 to a bore 236 in the bracket 54, from which it passes to the bearing support for the gear 32, and to the rear bearing for the drive shaft 36. Lubricant under pressure is directed through the conduit 222 and an associated drip plug 238 to the bearing support 52 for the spline gear 30 on the drive shaft 28. The conduit 224 and a drip plug 240 associated therewith, serve to direct lubricant to the rear bearing 64 for the overrunning clutch drive shaft 44. Similarly, the conduits 226, 228 and 230 having drip plugs connected therein, serve

to supply lubricant respectively to the front bearing 58 for the shaft 36, to the bearing 66 for the shaft 48, and to the bearing 62 for the shaft 44. The conduit 232 and a drip plug 244 connected therein, provide an additional outlet through which lubricant is permitted to drip onto certain other moving parts (not shown). It will be understood that each of the drip plugs associated with the several conduits leading from the secondary distributing head 196, is constructed and arranged to provide a predetermined resistance to the passage of lubricant therethrough, so that lubricant will be distributed to the several operating parts in properly proportioned amounts, which may be readily determined in accordance with the requirements of the particular bearings or other parts to be lubricated.

In accordance with a principal feature of the present invention, applicants' time delay valve 136 above referred to, is provided for controlling the admission of lubricant under pressure into the distributing system from the pump 132, which is continuously driven during power operation of the table, saddle and knee transmission. The valve 136, as hereinafter more fully pointed out, is constructed and arranged to introduce a sufficient quantity of lubricant into the system to provide a thorough lubrication of all the lubricating parts in starting the machine, and thereafter to shut off the supply. To this end, applicants' valve 136 is arranged to be controlled directly by variations in pressure existing in the system, operating to shut off the supply only after the pressure in the distributing system has been built up to a point which will insure a thorough lubrication of the several operating parts.

The construction and operation of the valve 136 will be best understood in connection with Fig. 3 of the drawings. The valve comprises the casing 249 and a plunger 250 which is supported for axial movement in a cylindrical bore 252 in the casing. Movement of the valve member 250 to the left is limited by engagement with a plug 254 in which is formed an inlet port 256 for the conduit 160. The valve member 250 is yieldingly maintained in its extreme position to the left by means of a compression spring 258, which is seated at one end in the recess 260 in the plunger 250, and at its other end in a plug 262 screw-threaded into a threaded portion of the bore 252. It will readily be seen that adjustment of the pressure exerted by the spring 258 is readily obtained by an adjustment in the position of the plug 262. The valve member 250 has formed therein a central bore 264 which connects at one end with the inlet 256 and conduit 160 for the admission of fluid under pressure from the pump 132. At its opposite end the bore 264 is connected by means of a number of radial ducts 266 with a peripheral groove 268 in the valve member 250, which provides connection with the outlet 164 and conduit 166 to the main distributing head 168 for the position of the parts shown in Fig. 3. Movement of the valve member 250 to the right, as hereinafter more fully set forth, operates to close off the outlet 164, and to align the peripheral groove 268 with the exhaust outlet 161 and return conduit 162 to the reservoir 130.

The operation of applicants' time delay valve 136 may be briefly described as follows: Assuming that the machine is in its stop position, and that the valve member 250 is in its position to the

extreme left as shown in Fig. 3, the starting of the table transmission including the gear 49 and shaft 50, will start the pump 132. Lubricant under pressure is now forced through the conduit 160 and through the axially extending bore 264, radial ducts 266 and groove 268 to the outlet 164, and thence through the main distributing head 168, from which lubricant is now supplied, as above set forth, in proportional amounts to the several operating parts of the machine. In this manner, a substantially continuous flow of lubricant under pressure is maintained to the several lubricated parts until a substantial amount of back pressure has been built up in the system. As soon as this happens, the valve member 250 is forced to the right against the pressure of its spring 258, thus closing off the outlet 164 and opening the exhaust outlet 161, so that all of the lubricant forced into the valve 136 by the pump is now returned to the reservoir 130. It will readily be seen that the valve member 250 will now be continuously maintained in a position to the right due to the pressure maintained by the pumping unit 132, so that no further lubricant will be supplied to the machine parts during continued machine operation. It will also be evident that upon stopping of the machine, no change will be effected immediately in the position of the valve member 250, since lubricant is locked in the supply conduit 160 through the operation of the check valve 158, so that the spring 258 is ineffective to return the plunger 250 to the left. However, in the course of time, assuming a certain amount of leakage between the plunger 250 and the cylindrical bore 252, the lubricant will be permitted to gradually drain outwardly through the radial ducts 266 and peripheral groove 268 passing between the bearing surfaces provided by the valve member 250 and bore 252, and thence through the outlet 161 and return conduit 162 back to the reservoir 130. As lubricant is permitted to escape in this manner, the spring 258 will gradually return the plunger 250 to the left until it finally reaches again the position shown in Fig. 3. The rapidity with which this return action takes place will, of course, be determined by the amount of the clearance which exists between the valve member 250 and bore 252, and upon the adjustment of the spring 258. While applicant does not propose to limit himself as to the length of the delay period in which the machine may again be started without causing an additional shot of lubricant to be distributed to the several bearings, it has been found desirable to adjust the valve 136 so that a period of inactivity amounting to the better part of an hour, must elapse before the valve member 250 will have returned to the operative position shown in Fig. 3.

It will be understood that the invention is not limited to the specific embodiment shown, and that various deviations may be made therefrom without departing from the spirit and scope of the appended claims.

What is claimed is:

1. A device for lubricating the moving parts of a machine tool which comprises means for supplying lubricant under pressure, means operative in starting and stopping said parts to start and stop said pressure supply means, a conduit through which lubricant supplied under pressure is directed to the parts to be lubricated, a control valve in said conduit comprising means responsive to variations in pressure for movement between open and shut-off positions, actuatable by

the building up of pressure of lubricant forced through the conduit to the parts to be lubricated in starting said parts to shut off the supply of lubricant, and pressure exhaust means operative in stopping said parts to gradually exhaust said pressure and thereby to permit the valve connection between the pressure supply means and said parts to open only after a substantial period of inactivity of the parts.

2. A device for lubricating moving parts in a machine tool which comprises means for supplying lubricant under pressure, means operative in starting and stopping said parts to start and stop said pressure supply means, a conduit through which lubricant supplied under pressure is directed to the parts to be lubricated, and a control valve in said conduit comprising a valve member and tensioning means acting thereon responsive to variations in pressure for movement between open and shut-off positions, actuatable by the building up of pressure in the conduit to shut off the supply of lubricant to the parts, and actuatable by the stopping of the pressure supply means to permit the valve to open, and means to retard the movement of the valve member to open position whereby the valve is opened only after a substantial period of inactivity of the parts.

3. A device for lubricating moving parts in a machine tool which comprises means for supplying lubricant under pressure, means operative in starting and stopping said parts to start and stop said pressure supply means, a conduit through which lubricant supplied under pressure is directed to the parts to be lubricated, a control valve in said conduit having means responsive to variations in pressure for movement between open and shut off positions, actuatable by the building up of pressure in the conduit to shut off the supply of lubricant to the parts, and actuatable by the stopping of the pressure supply means to permit the valve to open, and means for retarding the return movement of the valve to open position.

4. A device for lubricating the moving parts in a machine tool which comprises means for supply lubricant under pressure, means operative in starting and stopping said parts to start and stop said pressure supply means, a conduit through which lubricant supplied under pressure is directed to the parts to be lubricated, a control valve in the conduit responsive to variations in fluid pressure for movement between open and exhaust positions, an exhaust connection to the control valve, and means in the control valve operative in starting said parts to supply a limited quantity of lubricant thereto, and thereafter to by-pass lubricant under pressure to the exhaust connection, and means including a leakage exhaust connection operative in stopping said parts to permit the valve to return to open position only after a substantial period of inactivity of said parts.

5. A device for lubricating moving parts in a machine tool which comprises means for supplying lubricant under pressure, means operative in starting and stopping said parts to start and stop said pressure supply means, a conduit through which lubricant supplied under pressure is directed to the parts to be lubricated, a control valve in said conduit having means responsive to variations in pressure for movement between open and shut-off positions, actuatable by the building up of pressure in the conduit to shut off the supply of lubricant to the parts, and actuatable by a reduction of the supply pressure upon

5 the stopping of the pressure supply means to permit the valve to open, a check valve in the supply side of the conduit from the control valve to prevent reverse flow of lubricant out of the conduit, and means including a leakage connection for exhausting lubricant from the control valve at a slow rate whereby the valve is permitted to return to open position only after a substantial period of inactivity of said machine parts.

6. A device for lubricating bearing surfaces for moving parts housed by a movable machine tool support which comprises means actuatable by the movement of said parts for supplying lubricant under pressure, a conduit through which the lubricant is directed to the bearing surfaces, means to prevent the reverse flow of lubricant out of said conduit, and a control valve in the conduit having an exhaust connection thereto, a valve member having an operative position in which lubricant is permitted to pass through the conduit and the exhaust connection is shut off, and an alternative closed position in which the portion of the conduit extending to the lubricated parts is shut off, and the lubricant is exhausted through said exhaust connection, tensioning means tending to maintain the valve member in operative position, means responsive to the building up of pressure in said conduit for moving the valve member to closed position, and means including a leakage connection operative upon shutting off of the supply pressure for gradually exhausting said pressure to retard the return of the valve member under the influence of said tensioning means to operative position.

35 7. A device for lubricating a machine tool transmission having a plurality of moving parts, which comprises means for supplying lubricant under pressure, means operative in starting and stopping said parts to start and stop said pressure supply means, a distributing system including a distributing head and conduits therefrom constructed and arranged to distribute proportional amounts of lubricant to the parts to be lubricated, a control valve connected between the lubricant supply means and said distributing head responsive to variations in pressure for movement between open and shut-off positions including a valve member and tensioning means urging said valve member toward open position, actuatable by the building up of pressure in the distributing head to shut off the supply of lubricant to the parts, and actuatable by a reduction of the supply pressure upon the stopping of the pressure supply means to permit the valve to open, and lubricant pressure exhaust means including means operative upon stopping said pressure supply means to gradually exhaust said lubricant under pressure to permit the gradual return of the valve member to open position only after a substantial period of inactivity of the parts.

8. A device for lubricating moving parts housed in the knee support of a milling machine having a work supporting assembly including relatively movable table, saddle and knee supports and motion transmitting devices for said supports including a power driving element and a plurality of associated moving parts mounted in the knee, which comprises a reservoir in the knee, a pump connected to be driven by said driving element for forcing lubricant under pressure from the reservoir, a conduit through which lubricant supplied under pressure is directed for lubricating said moving parts in the knee, and a control valve

in said conduit responsive to variations in pressure for movement between open and shut-off positions comprising a valve member and tensioning means urging said valve member toward open position against said lubricant pressure actuatable in starting said driving element to supply a limited quantity of lubricant under pressure to said parts, and thereafter to shut off the supply of lubricant, and lubricant pressure exhaust means including means operative upon stopping said driving element and pump driven thereby to gradually exhaust said lubricant under pressure to permit the gradual return of the valve member to open position only after a substantial period of inactivity of the moving parts.

9. A device for lubricating moving parts housed in the knee support of a milling machine having a work supporting assembly including relatively movable table, saddle and knee supports, and motion transmitting devices for said supports including a power driving element and a plurality of associated moving parts mounted in the knee, which comprises a reservoir in the knee, a distributing system including a distributing head and conduits for distributing proportional amounts of lubricant to the lubricated parts, a pump operative for forcing lubricant under pressure from the reservoir to the distributing head, connections from the driving element for continuously operating the pump, and a valve responsive to variations in pressure for controlling the admission of lubricant from the pump to the distributing head, comprising a valve member responsive to the building up of pressure in said distributing system for movement from an open to a shut-off position, means urging the valve member toward open position, and lubricant pressure exhaust means including means operative upon stopping of the driving element and pump driven thereby to gradually exhaust said lubricant under pressure to permit a gradual return of the valve member to open position only after a substantial period of inactivity of the parts.

10. A device for lubricating moving parts housed in the knee support of a milling machine having a work supporting assembly including relatively movable table, saddle and knee supports, and motion transmitting devices for said supports including a driving element and a plurality of associated moving parts mounted in the knee, which comprises a reservoir in the knee, a distributing system including a distributing head and conduits for distributing proportional amounts of lubricant to the lubricated parts, a pump operative to force lubricant under pressure from the reservoir to the distributing head, connections from the driving element for continuously operating the pump, and a valve responsive to variations in pressure for controlling the admission of lubricant from the pump to the distributing head, comprising means actuatable by the building up of pressure in said distributing system to shut off the supply of lubricant to the distributing head, and actuatable by a reduction of the supply pressure upon the stopping of the driving element and pump driven thereby to permit the valve to open, and means for exhausting lubricant from the control valve at a slow rate whereby the valve is permitted to return to open position only after a predetermined period of inactivity of said driving element.

11. A device for lubricating moving parts housed in the knee support and associated feed box of a milling machine having a work support-

ing assembly including relatively movable table, saddle and knee supports, and including a feed box supported integrally with the knee, and motion transmitting means for said supports including a power driving element and a plurality of associated moving parts supported in the knee and in the feed box, which comprises a reservoir in the knee, a distributing system including a distributing head, and conduits for distributing proportional amounts of lubricant to the moving parts carried by the knee, a second distributing head, and conduits therefrom for distributing proportional amounts of lubricant to the moving parts in the feed box, a pump through which lubricant is directed under pressure from the reservoir to the first and second distributing heads, connections from said power driving element for continuously operating the pump, and a control valve between the pump and said distributing heads comprising means responsive to variations in pressure, actuatable by the building up of pressure in said distributing system to shut off the supply of lubricant to the distributing heads, and means operative to re-open the valve only after a predetermined period of inactivity of said power driving element and pump driven thereby.

12. A device for lubricating the moving parts in a machine tool which comprises means for supplying lubricant under pressure, means operative in starting and stopping said parts to start and stop said pressure supply means, a conduit through which lubricant supplied under pressure is directed to the parts to be lubricated, and a control valve in said conduit including a valve member responsive to the building up of pressure in the conduit for movement from an open to a shut-off position, means urging the valve member toward open position, and lubricant pressure exhaust means including means operative upon stopping said pressure supply means to gradually exhaust said lubricant under pressure to permit the gradual return of the valve member to open position only after a substantial period of inactivity of the parts.

13. A device for lubricating the moving parts in a machine tool which comprises means for supplying lubricant under pressure, means operative in starting and stopping said parts to start and stop said pressure supply means, a conduit through which lubricant supplied under pressure is directed to the parts to be lubricated, and a control valve in said conduit including a valve member responsive to the building up of pressure in the conduit for movement from an open to a shut-off position, means urging the valve member toward open position, and lubricant pressure exhaust means including means operative upon stopping said pressure supply means to retain the lubricant under pressure in the conduit, and fluid pressure exhaust means including a leakage connection for exhausting said lubricant under pressure to permit the gradual return of the valve member to open position only after a substantial period of inactivity of the parts.

14. A device for lubricating the moving parts in a machine tool which comprises means for supplying lubricant under pressure, means operative in starting and stopping said parts to start and stop said pressure supply means, a conduit through which lubricant supplied under pressure is directed to the parts to be lubricated, and a control valve in said conduit including a casing having at one end a pressure inlet port and pressure outlet and exhaust ports spaced in that order

from the inlet port, and including a valve member slidable in the casing having a conduit extending axially from the end of the valve member connecting with the inlet port, and a radially exposed extension of said conduit connecting alternately with said pressure outlet and pressure exhaust ports, tensioning means urging the valve member toward open position connecting the inlet with the pressure outlet port, means to prevent reverse flow of lubricant from the inlet port upon stopping said pressure supply means, the valve member having a leakage connection between said conduit and the exhaust port whereby the valve member is permitted to return to open position under the influence of said tensioning means only after a substantial period of inactivity of the machine parts.

15. A device for lubricating the moving parts in a machine tool which comprises means for supplying lubricant under pressure, means operative in starting and stopping said parts to start and stop said pressure supply means, a conduit through which lubricant supplied under pressure is directed to the parts to be lubricated, a con-

trol valve in said conduit including a cylindrical casing having at one end thereof a pressure inlet port and pressure outlet and pressure exhaust ports spaced in that order from the inlet port, and 5 including a valve member slidable within the casing having a conduit extending axially from the end of the valve member connecting with the inlet port, and radially exposed extensions of said conduit connecting alternately with said pressure outlet and pressure exhaust ports, tensioning means urging the valve member toward open position connecting the inlet with the pressure outlet port, a check valve in the supply side of the conduit from the control valve to prevent reverse flow of lubricant in the inlet port, said valve member having a loose fit with the casing to provide a leakage connection operative upon stopping of the pressure supply means to permit the gradual exhaust of said lubricant under pressure and the return of the valve member to open position only after a substantial period of inactivity of the machine parts.
